BRAKE RIGGING

Jesse F. Holloway, Aldan, Pa.

Application June 17, 1938, Serial No. 214,340

1 Claim. (Cl. 188—212)

This invention relates generally to brake rigging and more particularly to improved means for maintaining a brake head in concentric relation to a wheel, and it is an object of my invention to provide a relatively simple, rugged and conveniently adjustable means for maintaining a brake head in concentric relation to its wheel whereby the construction of said means is compact, sturdy and economical in manufacture, maintenance and operation. The subject matter of this application is disclosed in my Patent No. 2,110,992, issued March 15, 1938.

Other objects and advantages will be more apparent to those skilled in the art from the following description of the accompanying drawing in which:

Fig. 1 is a plan view of my improved brake rigging applied to a truck only one-half of which is shown;

Fig. 2 is a side elevation of Fig. 1;

Fig. 3 is an elevation of the right end of Fig. 2;

Fig. 4 is an enlarged fragmentary side elevation of the lower end of the brake hanger and brake head showing the means for maintaining the brake shoe concentric with the wheel;

Fig. 5 is an elevation of Fig. 4, viewed in the direction of arrow A, Fig. 4;

Fig. 6 is a section on line 6—6 of Fig. 4.

In the particular embodiment of the invention, such as is disclosed herein merely for the purpose of illustrating one specific form among possible others than the invention might take in practice, I have diagrammatically shown a conventional truck having usual side sills 1, end sills 2 and a transom 3 supported upon a pair of wheeled axle units 4 and 5. Usual journal boxes, springs and equalizing beams, as well as other usual truck features, may be employed but are omitted for sake of clarity inasmuch as they do not constitute a part of my present invention. It will of course be understood that the braking apparatus and truck structure are identical and symmetrical on both sides of its center line and hence the description of one side will suffice for both.

Each wheel is provided with clasp brake heads and shoes 6 and 7, and 8 and 9 pivotally supported as at 10 to 13 on vertical levers 14 to 17 whose upper ends are pivotally supported to the truck frame as indicated at 18 to 21. The lower ends of the brake levers are pivotally connected as at 22 to 25 to horizontal equalizing levers 26 to 29 whose inner and outer ends terminate respectively in planes located on the inside and outside of the wheel. Axially adjustable tension rods 30 and 31 pivotally connect together the

outer ends of equalizing levers 26 and 27, and 28 and 29 while a compression rod 32 pivotally connects the inner ends of equalizing levers 27 and 28. A transverse rod 32' pivotally connects the compression rods 32 on each side of the truck to assist in laterally stabilizing the brake rigging. The pivots 22 to 25 for the transverse equalizing levers lie substantially in the vertical plane of the wheels and of the vertical brake levers 14 to 17. By reason of the equalizing levers 26 to 29 extending to the inner and outer sides of the wheel planes, it is possible to have pivots 22 to 25 located symmetrically with respect to the vertical plane of brake levers 14 to 17, it being understood that the lower ends of said levers are turned horizontally to provide a horizontal clevis 43 (Fig. 4) to receive the equalizing levers. A tension rod 33 (Fig. 1) is pivotally connected as at 34 to the truck frame while its other end is pivotally connected to the inner end of equalizing lever 26.

A compression link 35 (Fig. 2) is pivotally connected in either one of a plurality of adjustable pivot positions 37' to a vertical operating arm 36 which is secured to the inner end of a transverse shaft 37. This shaft is suitably journaled in the truck frame and has a vertical cylinder lever 38 secured to its outer end for pivotal attachment as at 39 to a cylinder push rod 40. This rod as is usual is attached to the piston within brake cylinder 41 which is preferably secured to the truck side sill 1 as by bolts 42 in any suitable manner.

The particular improvement of this application consists in having each brake shoe maintained in concentric relation to its wheel by a spring 35 pressed plunger 45 (Fig. 6) slidably supported in a sleeve 46 which has adjustable threaded connection with an ear 47 formed on the side of the brake hanger 15. The spring 48 is thus entirely closed and readily adjustable. The sleeve is locked in position by a jam nut 49. The plunger bears against a lug 50 formed on the brake head 7. The ears and lugs such as 47 and 50 are duplicated on each side of the brake head and hanger to permit interchangeable use thereof in left or right hand positions. The adjusting means are associated only with the lugs and the ears which assume a position on the outside of the truck, thereby rendering the adjustable means readily accessible. It will of course be understood that the foregoing construction is identical for each set of brake heads and hangers. As a result of this improved arrangement it is seen that I have provided a very simple and yet sturdy arrangement for holding the brake shoes concentric to 55

the wheels when the brake is off without any possibility of the spring dropping out of position during service regardless of the lack of attention to the equipment.

5 In operation, the brakes are applied by causing the brake cylinder piston to move compression rod 40 to the right, thereby causing arm 38 to swing in a clockwise direction and rotate shaft 37 and lever 36, whereupon compression link 35 10 moves equalizing lever 29 and its brake head pivotal connection 25 toward the wheel. Engagement of the brake shoe with the wheel causes equalizing lever 29 to move about its pivot 25 and accordingly pull on tension rod 31 and thereby 15 move lever 28 and pivot 24 so as to cause brake head 8 to press its shoe against the wheel. Thereupon compression rod 32 functions to operate the equalizing levers and rods 27, 30 and 26 to move the brake heads 6 and 7 toward its wheel. Link 20 33 provides the necessary reaction force between the truck frame and the final end of the train of brake rigging levers and rods. The foregoing operation is rendered fully effective with minimum application of force by virtue of the brake heads being maintained in concentric relation to the wheels while still permitting the brake heads to yield both forwardly and backwardly by reason of spring plungers 45 and their abutting contacts with lugs 50 of the brake heads.

25 30 From the foregoing disclosure it is seen that I

have provided a relatively simple, compact and yet efficient means for maintaining the brake heads in concentric relation to the wheels without imposing any limitations on the brake rigging or its operation, together with having a concentric maintaining means that is economical in manufacture, maintenance and operation with the parts readily accessible for adjustment, inspection and repair while at the same time maintaining the desired degree of flexibility and ruggedness. 5 10

It will of course be understood that various changes in details of construction and arrangement of parts may be made by those skilled in the art without departing from the spirit of the 15 invention as set forth in the appended claim.

I claim:

A brake control mechanism for a railway truck having a brake lever member and a brake head member pivotally supported thereby comprising, 20 a hollow sleeve having threaded adjustable connection with one of said members, a hollow plunger engageable with the other of said members and being telescopically slidably supported by said sleeve for normal movement relative 25 thereto, and a spring disposed within said plunger and sleeve for yieldingly pressing said plunger into its said engagement.

JESSE F. HOLLOWAY. 50
